CLAIM

The ornamental design for a ceiling fan housing, as shown and described.

DESCRIPTION

FIG. 1 is a perspective view of a ceiling fan housing in accordance with my design;

FIG. 2 is a top plan view thereof;

FIG. 3 is a bottom plan view thereof;

FIG. 4 is a left elevation view thereof, the opposite side being a mirror image of that shown; and,

FIG. 5 is a front elevation view thereof, the opposite side being a mirror image of that shown.

The broken lines in the drawings illustrate environmental subject matter and form no part of the claimed design.
